HOMER S. ROGERS AND RICHARD RADDATZ, OF MILWAUKEE, WISCONSIN, ASSIGNEES
TO MILWAUKEE AIR POWER PUMP CO., OF MILWAUKEE, WISCONSIN, A CORPOR-
ATION OF WISCONSIN

PNEUMATIC PUMP

Application filed May 17, 1926. Serial No. 109,590.

This invention relates to improvements in pneumatic pumps of the type used for elevating water from wells by air pressure, and more particularly to the mechanism for and the method of actuating the fluid inlet and exhaust valves.

Pumps of the character referred to comprise, in general, a pumping chamber having water inlet and outlet ports, fluid inlet and outlet ports, valves for opening and closing these ports, and some means for causing opening and closing of the fluid exhaust and inlet valves, respectively, when the water in the pump chamber reaches the low level point and for causing reverse operation of these valves when the water reaches the high level point. Various mechanisms have been devised for causing this operation of the fluid valves, one of these mechanisms including an operating float arranged in the pump chamber and connected in suitable manner to the fluid exhaust valve for pulling the latter from its seat at low level condition in the pump chamber, this valve being arranged in each case to close with the pressure in the latter. This float has operated with more or less satisfaction under relatively low pressures, but where the higher pressures are used as in some of the present day systems, the float has been found to be insufficient to insure proper action of the fluid exhaust valve against the internal pressure in the pump chamber. Even under low pressure conditions, in this valve actuating mechanism, if discharge of water from the pump chamber is stopped or continued to a relatively slow rate at the instant the low water level point is reached, the movement of the float will be insufficient to completely unseat the fluid exhaust valve, resulting in an intermittent seating and partial unseating of said valve, improper operation of the pump and leakage of the air pressure.

For the purpose of providing against this dead-center position, which is possible with the fluid valve actuating mechanism of this latter type, and to provide for rapid and certain actuation of the fluid valves at low level condition in the pump chamber, it has been proposed to employ a fluid pressure motor connected to the fluid valves and operable by the

working pressure for the pump to actuate the valves against the internal pressure in the pump chamber when the water level in the latter reaches its lowermost point. While use of such a motor for the purpose explained has been found to eliminate the disadvantages of the valve actuating mechanism of the float-actuated type, it has made necessary an increase in the number of operating parts and a corresponding increase in the cost of manufacture of the pump.

One of the objects of the present invention is to provide, in a pump of the character referred to, improved actuating mechanism for the fluid exhaust and inlet valves, this mechanism being of the float-actuated type and having the advantages of the prior construction of this type as regards simplicity and cost of manufacture while eliminating the so-called "dead-center" position at low level in the pump chamber, and having the advantages of such mechanism employing a fluid pressure motor as regards the relatively rapid and certain actuation of the fluid valves which is possible in this latter type of mechanism when the water in the pump chamber reaches the low level point.

Another object is to provide, in a pump of the character referred to, improved actuating mechanism for the fluid valves wherein a predetermined amount of potential energy is stored up during discharge of water from the pump chamber and wherein means are provided to release and permit utilization of this potential energy in causing opening and closing of the fluid exhaust and inlet valves, respectively, when the water in the pump chamber reaches the low level point.

Another object is to provide an improved method for effecting opening movement of the fluid exhaust valve, in a pump of the character referred to, wherein a predetermined amount of potential energy is stored up during discharge of the water from the pump chamber and is subsequently released and utilized in causing this movement of the exhaust valve when the water in the chamber reaches the low level point.

Other objects and advantages will herein-after appear.

For the purpose of illustrating the invention, one embodiment thereof is shown in the drawing, the latter being a vertical sectional view through the pump, partly broken away.

The pump casing 10 is provided with a water inlet port 11 controlled by a suitable check valve 12 arranged as shown to close with the pressure in the pump chamber 13, and an auxiliary opening 14 which is closed or sealed by a suitable valve 15 arranged to seat with the pressure in chamber 13 and provided with a guiding stem 16 fitting loosely in opening 14, valve 15 being provided with an operating rod 17 pivotally connected thereto at 18 and provided with a head 19 for the purposes hereinafter explained.

The upper end of casing 10 is closed by a head member 20 secured thereto in any suitable manner and provided with a fluid exhaust passage 21, a fluid inlet passage 22, and a water outlet passage 23 in which is arranged a suitable check valve 24 opening with the pressure in chamber 13. For the purpose of conveying water from the pump chamber 13 to the water outlet passage 23, a pipe 25 is threaded at its upper end into the underside of head member 20 and extends downwardly to within a relatively short distance from the bottom of casing 10, the upper end of pipe 25 communicating with passage 23 and being controlled by valve 24.

The fluid exhaust passage 21 is closed and opened by the valve 26 arranged to seat or close with the pressure in chamber 13 and provided with a bent arm 27 pivotally connected at 28 to head member 20, valve 26 being further provided with a depending lug 29 for the purpose hereinafter explained. The fluid inlet passage 22 is controlled by the valve 30 arranged to seat or close against the pressure in passage 22 and connected to the outer end of arm 27 by a link 31.

A link 32 is pivotally connected at 33 to valve 26, and a similar link 34 is pivotally connected at 35 to a lug 36 which may be formed integrally with head member 20, the adjacent ends of these links being pivotally connected together by means of a pin 35 to which is also connected a hanger 37 provided at its lower end with a weighted head 38.

A lever 39 is pivotally mounted on a pin 40 fixed in a lug 40' which may be formed integrally with head member 20, as shown, and is provided with an upwardly extending lug 41 and a vertical opening 42 through which hanger 37 loosely passes. The short arm 43 of this lever is provided at its end with an opening 44 through which rod 17 loosely passes and with a seat 45 for the head 19 at the upper end of this rod. A float 46 is pivotally connected at 47 to the end of the long arm 48 of lever 39.

The operation of the improved pump will now be described, starting with the parts in 65 their respective positions as shown in the

drawing, wherein the fluid exhaust valve 26 is closed and the fluid inlet valve 30 open to place the pump chamber 13 under pressure and force the water therefrom through pipe 25, valve 24 and water outlet passage 23. 70 As the water level in chamber 13 drops, there will be less buoyant action on float 46, and when the water level drops to a certain point float 46 will begin to act as a weight and tend to pull lever arm 48 downwardly. 75 As the water level in chamber 13 drops further and approaches the lower end of float 46, the downward pull of the latter on arm 48 increases. The pressure on the upper side of valve 15 during discharge 80 of the water from chamber 13, however, is sufficient to hold lever 39 against clockwise movement about pin 40 as a center, the head 19 of rod 17 engaging seat 45 to hold lever 39 against this movement by the downward pull 85 of float 46 on lever arm 48. It will thus be seen that during discharge of water from chamber 13 float 46 will store up a certain amount of potential energy. The relation between the working pressure and the area of valve 15 is such that when the level of the water has dropped to a point a short distance from the lower end of float 46 the effective weight action of the latter, which acts upwardly upon head 19 of rod 17 and which is 90 multiplied by lever 39, is sufficient to pull valve 15 from its seat, at which time float 46 is free to drop under the action of gravity. Just before float 46 reaches the end of its drop, at which time it has the maximum of kinetic 100 energy, lever 39 engages head 38 with an impact, and through hanger 37 and the toggle mechanism comprising links 32 and 34 jerks exhaust valve 26 free of its seat and closes the fluid inlet valve 30. Water will then enter 105 the pump chamber by way of inlet port 11, some water also entering the chamber at this time by way of the auxiliary port 14. As the water level in chamber 13 rises, float 46 will also rise to permit valve 15 to close. Further 110 upward movement of float 46 with the water level will cause lug 41 to engage lug 29 of valve 26 whereby the latter is closed and the fluid inlet valve opened, the arrangement being such that valve 30 is fully opened slightly before valve 26 seats whereby seating of the latter is effected with a quick snap action by the air pressure entering chamber 13, this pressure being sufficient to hold valve 26 closed against the downward pull thereon due 120 to the weighted head member 38. The water is then again forced from chamber 13 by the fluid pressure acting on the surface thereof, float 46 dropping with the water level until seat 45 at the outer end of lever arm 43 engages head 19 at the upper end of rod 17, at 125 which time float 46 is held against further downward movement by the action of the pressure on the upper side of valve 15, thus completing the cycle. 130

The combined weight of valve 26, links 32 and 34, hanger 37 and member 38 is sufficient to hold valve 26 open and valve 30 closed against the pressure in passage 22 after lever 39 engages member 38 to jerk valve 26 from its seat in the manner explained.

By extending the water outlet pipe 25 below the lower end portion of float 46, the latter determining the low water level point in the manner explained, the lower or inlet end of pipe 25 is always water-sealed to prevent entrance of air into this pipe.

From the foregoing it will be seen that improved actuating mechanism for the fluid exhaust and inlet valves of a pneumatic pump of the character described has been provided wherein a single float is used for operating the valves in both directions and wherein a predetermined amount of potential energy is stored up during discharge of the water from the pump chamber and is released and utilized to jerk the fluid exhaust valve from its seat against the internal pressure with a quick and positive action at low level.

It will be further seen that when the water in chamber 13 reaches the low level point and valve 15 is started from its seat by the weight action of float 46, the float will drop instantly to cause impact of lever 39 on head 38 to effect opening of valve 26 and closing of valve 30 although at this instant the withdrawing of water from the pump chamber may be stopped or continued at a relatively low rate. There is, therefore, no possibility of a "dead-center" position.

Although one embodiment of the invention has been shown and described, it will be appreciated that various changes may be made such as in the size, shape and arrangement of the parts, without departing from the spirit of the invention or the scope of the claims.

The invention claimed is:

1. In a pneumatic pump, the combination with a pumping chamber and the fluid exhaust valve thereof, the latter being arranged to close with the pressure in the pump chamber, of means for causing said valve to open and including a plurality of disconnected parts supported for movement into spaced relation with respect to each other to permit closing of said valve and for movement into engaging relation with each other to effect opening of the latter, means responsive to high level condition in said chamber for placing said parts in said spaced relation and tending under low level condition in the pump chamber to cause movement of said parts into said engaging relation, and means arranged for coaction with said first-named means for releasably holding said parts in said spaced relation and acting to permit said second-named means to store up a predetermined amount of potential energy dur-

ing discharge of the water from said chamber and until the water level in the latter reaches the low point, said last-named means yielding at this time to the action of said second-named means whereby said stored energy thereof is released to cause said parts to engage with each other with an impact to effect opening of said valve against the existing pressure in the pump chamber.

2. A pneumatic pump having a pump chamber, a fluid pressure exhaust valve associated therewith and closing with the pressure in the pump chamber, operating mechanism for imparting operative movements to said valve, a vent below the low water level in the chamber, a vent controlling valve, a lever fulcrumed within the chamber and operatively connected to the vent controlling valve and to the operating mechanism for the fluid pressure exhaust valve, and a float connected to said lever, the area of the vent controlling valve, the weight of the float and the ratio of the arms of the lever being so proportioned to each other and to the working pressure in the pump chamber that when the level of the water has dropped to a point a short distance below the lower end of the float, the float drops under the action of gravity to move the vent controlling valve away from its vent and to actuate the operating mechanism for the valve.

In witness whereof we hereto affix our signatures.
